THROTTLE CONTROL DEVICE

Clifford Stone Drabble, Windsor, Ontario, Canada

Application November 4, 1940, Serial No. 364,219

7 Claims.

(Cl. 192—3)

This invention relates to control devices for carburetor throttles of internal combustion engines.

In present day automotive vehicles, there is usually provided two control means for the engine throttle, namely, a foot-operated accelerator rod, which is spring-urged to closing position, and a hand-operated throttle rod, which may be set in any position. Under normal driving conditions, the throttle is controlled by the foot accelerator, the hand-operated rod being employed only occasionally, such as at times in starting the engine. In driving long distances, a vehicle operator frequently suffers strain in the foot operating the accelerator since such foot must be maintained in one position over a long period of time. Moreover, road shocks transmitted to the foot cause uneven feeding of the fuel mixture and consequent uneven speed and added gasoline consumption.

It is an object of the invention to provide means associated with the foot accelerator, for automatically locking the throttle in any open position to which it may be moved by the accelerator whereby the foot may be removed from the accelerator and the throttle maintained at such fixed open position, together with means, preferably associated with other vehicle control means, for unlocking said locking means.

The invention will be described with reference to the accompanying drawing, in which,

Figures 1 and 2 are side elevations of the device in two operating positions, and

Figure 3 is an end elevation.

The device is shown in the drawing as applied to a carburetor 1 of standard design having a throttle valve 2 mounted on a throttle shaft 3 and adapted to supply fuel mixture to the intake manifold 4 of an automotive vehicle internal combustion engine (not shown). The usual foot-operated accelerator rod 5, connected to the throttle shaft, is provided. Instead, however, of the usual hand connection to the throttle shaft, there is provided an automatic lock comprising a sector-shaped ratchet plate 6 fixed to one end of the shaft and having ratchet teeth 7 in the arc edge thereof.

Positioned adjacent the ratchet plate is a small cylinder 8 having a lateral extension 9 thereon by means of which it may be conveniently mounted, as by a bolt 10, on the carburetor flange 11. The cylinder has a closed end 12 and an open end 13 and contains a reciprocable piston 14, which is normally urged into contact with the closed end by means of a spring 15, seated in a cylindrical depression 16 in the piston end and secured in position by a pin 17 in the cylinder wall and extending across the open end of the cylinder.

In the upper portion of the cylinder wall there

is provided a substantially rectangular opening 18, and extending through such opening is a raised portion 19 formed on the piston and having a curved cam surface 20 on one side thereof. 5 As shown, the portion 19 is shorter in length than the opening 18 and thus permits a reciprocating movement of the piston, such movement towards the open end of the cylinder being limited by contact of the surface 20 with the end edge of the opening, as shown in Figure 2. 10 A pawl 21 is pivotally mounted on a pin 22 between a pair of ears 23 extending upwardly from the upper surface of the cylinder. One end of the pawl is adapted for engagement with the ratchet 7 and the other end has a portion 24 extending downwardly into the cylinder opening 18 and having a curved cam surface edge 24' adapted to cooperate with the cam surface 20 on the raised piston portion 19. It will be noted that, 15 with the parts in the position shown in Figure 1, the pawl is in engagement with the ratchet, the piston being in contact with the closed end of the cylinder. Reciprocation of the piston to the left causes upward movement of the end 24 of the pawl by contact of the cooperating cam surfaces 24' and 20. The other end of the pawl is thereby moved out of engagement with the ratchet, as shown in Figure 2.

Means for locking the parts in the position shown in Figure 2, with the pawl and ratchet disengaged, comprises a dog 25, pivotally mounted on the pin 22 and having a downwardly extending end 25' urged downwardly by the spring 26 connected to an upwardly extending arm 27 on the dog and to the cylinder 8. It will be observed that, with the parts in the position shown in Figure 1, the dog engages the top surface of the raised portion 19 of the piston, but on reciprocation of the piston to the left, the dog drops over the end of raised portion 19 into the position shown in Figure 2 and prevents return reciprocation of the piston to the right, thus maintaining disengagement of the pawl and ratchet.

Means for manually moving the dog upwardly 45 out of engagement with the end of raised portion 19 to permit return reciprocation of the piston to the right and engagement of pawl and ratchet comprises a wire connection 28 between the arm 27 and a pull button 29 on the dash 30 of the vehicle. A rearwardly extending stop 33 is formed on the dog.

Any suitable power or manual means may be employed for effecting reciprocation of the piston to the left, as viewed in the drawing, to 55 disengage the pawl from the ratchet. Thus, an electrical, mechanical, or vacuumatic connection may be provided for the purpose. However, a preferred manner is illustrated diagrammatically in the drawing and comprises a conduit 31, communicating with a hydraulic brake

fluid conduit 32 of the vehicle, and leading into the interior of the cylinder through the closed end thereof, as illustrated. Thus, on application of the brake of the vehicle, and placing of the fluid in conduits 31 and 32 under pressure, such fluid under pressure forces the piston to the left against the action of spring 15. It follows that the throttle locking means, comprising the pawl and ratchet described, becomes automatically disengaged whenever the brake of the vehicle is applied.

The operation of the device will be apparent from the foregoing description. With the parts in the position shown in Figure 2, the pawl and ratchet control means is maintained in inoperative position, by the dog 25 and the vehicle throttle controlled by the driver in normal manner by means of the accelerator. When the driver desires to set the throttle at a fixed speed, he pulls button 29 to disengage dog 25 and effect engagement of the pawl and ratchet. Thereafter, he opens the throttle by means of the accelerator until the desired speed is reached, and the throttle is maintained in its farthest open position by the pawl and ratchet. If it is necessary to reduce speed and the brakes are applied, the pawl and ratchet connection is automatically broken by reciprocation of the piston to the left in the manner previously described.

There is thus provided a device which may be conveniently placed in fully automatic operation to lock the throttle in any open position to which it may be moved by the driver and wherein the throttle lock may automatically be broken by actuation of another vehicle control means such as the brake. The device thus makes possible the convenient setting of the throttle during long distance driving and the resultant avoidance of foot strain and uneven fuel mixture feeding.

I claim:

1. In an automotive vehicle having a carburetor, a throttle shaft therein and a throttle valve on the shaft, ratchet means fixed to one end of the shaft, a pawl adjacent said ratchet means, and means for placing said pawl into and out of engagement with said ratchet means comprising a cylinder having a reciprocatable piston therein, a cam member carried by the piston and a cooperating cam member carried by said pawl.

2. In an automotive vehicle having a carburetor, a throttle shaft therein and a throttle valve on the shaft, ratchet means fixed to one end of the shaft, a pawl adjacent the ratchet means, and means for placing said pawl into and out of engagement with the ratchet means comprising a cylinder having a piston thereon, a cam member carried by the piston, a second cam member carried by the pawl and engageable by said first cam member, spring means for reciprocating the piston in one direction and fluid pressure means for reciprocating the piston in the opposite direction.

3. In an automotive vehicle having a carburetor, a throttle shaft therein and a throttle valve on the shaft, ratchet means fixed to one end of the shaft, a pawl adjacent the ratchet means, means for placing said pawl into and out of engagement with the ratchet means comprising a cylinder having a piston therein, a cam member carried by the piston, a second cam member

carried by the pawl, and engageable by said first cam member, spring means for reciprocating the piston to a position in one direction to permit engagement of said pawl and ratchet means by cooperative movement of said cam members, and other means for reciprocating the piston to a position in the opposite direction to effect disengagement of said pawl and ratchet means by cooperative movement of said cam members, a spring-urged dog for locking the piston in said last-mentioned position, and manually actuated means for releasing said dog.

4. In an automotive vehicle having a carburetor, a throttle shaft therein and a throttle valve on the shaft, a member fixed to one end of said shaft for revolution therewith, a second member engageable with said first member and operable to prevent revolution of said shaft and first member in one direction while permitting revolution in the reverse direction, means responsive to actuation of a vehicle control member for placing said second member in inoperative position, latch means locking said second member in inoperative position whenever placed therein, and manually operated means for unlocking the latch means.

5. In an automotive vehicle having a carburetor, a throttle shaft therein and a throttle valve on the shaft, a member fixed to one end of said shaft for revolution therewith, a second member engageable with said first member to prevent revolution of said shaft and first member in one direction while permitting revolution in the reverse direction, means responsive to actuation of a vehicle control member for moving said second member out of engagement with said first member, latch means locking said second member in disengaged position whenever placed therein, manually operated means for unlocking the latch means and means operating automatically on unlocking of the latch means for permitting said second member to move into engagement with said first member.

6. In an automotive vehicle having a carburetor frame, a throttle shaft journalled therein and a throttle valve on the shaft, a segmental ratchet fixed to one end of the shaft for revolution therewith, a pawl engageable with said ratchet and having a pivotal mounting fixed with respect to said frame, means responsive to actuation of a vehicle control member for moving said pawl out of engagement with the ratchet, latch means locking said pawl in such disengaged position whenever moved therein, manually operated means for unlocking said latch means and means for permitting said pawl to move into engagement with the ratchet.

7. In an automotive vehicle having a carburetor frame, a throttle shaft journalled therein and a throttle valve on the shaft, a segmental ratchet fixed to one end of the shaft for revolution therewith, a support fixed to said frame, a pawl having a pivotal mounting in said support, spring means urging said pawl into engagement with said ratchet, means responsive to actuation of a vehicle control means for moving said pawl out of engagement with said ratchet, a locking dog carried by said pawl and engageable with said support to lock said pawl in disengaged position whenever moved therein, and manually operated means for unlocking said locking dog.
